ATTORNEY

WITNESS:

UNITED STATES PATENT OFFICE.

WILLIAM Z. MUSGRAVE, OF CINCINNATI, OHIO.

MATCH BOX.

Application filed April 23, 1921. Serial No. 463,795.

To all whom it may concern:

Be it known that I, WILLIAM Z. MUSGRAVE, a citizen of the United States, residing at Cincinnati, in the county of Hamilton and State of Ohio, have invented new and useful Improvements in Match Boxes, of which the following is a specification.

This invention relates to a match box, and the object is to provide a receptacle designed to be carried in the pocket, and provided with means for shielding a lighted match and a cigar being lighted.

A further object is to provide a box formed with a slideable shield adapted to serve the purpose indicated.

Another object is to provide a receptacle constructed in the manner hereinafter specified, and provides in connection therewith a shield having the form of a tubular element, 20 rectangular in cross section, one surface being roughened or corrugated, and one of the side walls being slotted to accommodate a lighted match.

With the foregoing and other objects in view, the invention consists in the novel construction, combination and arrangement of elements hereinafter described and claimed, it being understood that modifications may be made within the scope of the 30 claims, without departing from the spirit of the invention.

In the drawings, Figure 1 is a perspective view of the device; Figure 2 is a view in longitudinal section; Figure 3 is a side elevation, with a portion in section; Figure 4 is a transverse section; Figure 5 is a perspective view of an element adapted to connect the approaching edges of the sheet metal box and also retain the spring for the cover.

The body of the receptacle is designated 10 and may be formed of a single sheet of metal bent to produce a box approximately rectangular in cross section. The approaching edges 11 and 12 are slotted at intervals as shown at 13, and an inner connecting strip or plate 14 is provided with ears 15 which pass through the slots, and are then deflected or bent over into intimate engagement with the outer surface of the box. I do not limit myself to this particular type of connection, as any box of suitable construction may be employed. The bottom of the box is designated 16 and is formed 50 with a flange 17 which fits over the adjacent end of the body of the box.

The cover 18 is connected by means of a hinge 19 with the body portion, a suitable gasket 20 being provided to prevent the entrance of moisture. Projecting elements 22 60 formed on the hinge are engaged by a flat spring 24 which passes under the connecting plate mentioned above and is thereby retained in proper position for the purpose intended. The cover is provided with a 65 projecting element 26 formed by punching from the inner side of the flanged cover, this element serving as an engaging device to permit of the opening of the cover. The body of the receptacle is provided with 70 beads 27 and 28, and projecting elements 30 formed by punching from the inner side are provided for securing the bottom to the box per se.

The wind shield 31 includes four side 75 walls and constitutes a tubular element having a slot 32 formed in one end thereof for the accommodation of the lighted match. One wall of the tubular member is roughened or provided with corrugations 33, 80 serving an obvious purpose. The element 31 is slightly greater in cross section than the body of the box so that the walls of the box are spaced from the inner wall of the element 31, the thickness of the bottom and 85 of the adjacent bead surrounding the box accounting for the difference.

The tubular member 31 may if desired be formed of sheet metal, the approaching edges overlapping as shown at 31' and being 90 connected by soldering, or in any other suitable manner. A metallic frame 40 is suitably connected with one surface of the element 31, the frame including inwardly turned flanges 42 and a projecting element 95 43 at one end. The frame per se is spaced from the surface of the element 31, and advertising matter may be inserted within the frame after which the projecting element is bent over and acts as a retaining device. It is obvious that the owner's card or a photograph may be substituted for the advertising matter. The device is intended for use either as an advertising medium or as an article for sale and in the 100 latter event, it may be of more expensive material and more elaborately decorated.

What is claimed is:

1. A device of the class described, comprising a receptacle formed of sheet material bent in the form of a box, the approaching edges of the sheet being provided 110

with slots spaced inwardly from said edges, a strip including laterally extending ears, the ears being proportioned to pass through the aforesaid slots and to be bent into intimate contact with the outer wall of the box, and means for closing the ends of said receptacle, said box being formed with a bead projecting from the outer surface, and a tubular element within which the box is 10 slideable, said bead preventing engagement of the ears with the end of the tubular element.

2. A device of the class described, comprising a sheet of material bent in the form 15 of a box having approximately a rectangular cross section, the approaching edges of the sheet being provided with slots, a strip located within the receptacle and including

ears proportioned to pass through the slots and adapted to be bent over into contact with the outer wall of the receptacle, a cover, a hinge for connecting the cover with the body of the receptacle, the hinge including a projecting element, and a spring engaged by said element and passing between the aforesaid strip and the adjacent wall of the receptacle, the spring being retained by the strip, said box being formed with a bead projecting from the outer surface, and a tubular element within which the box is slideable, said bead preventing engagement of the ears with the end of the tubular element.

In testimony whereof I affix my signature.

WILLIAM Z. MUSGRAVE.
